UNITED STATES PATENT OFFICE

146,600

DESIGN FOR A VASE

Joseph Gmeindl, Milwaukee, Wis.

Application January 16, 1946, Serial No. 125,590

Term of patent 14 years

(Cl. D29—28)

To all whom it may concern:

Be it known that I, Joseph Gmeindl, a citizen of the United States, residing at Milwaukee, in the county of Milwaukee and State of Wisconsin, have invented a new, original, and ornamental Design for a Vase, of which the following is a specification, reference being had to the accompanying drawings forming a part thereof.

In the drawings:

I claim:

The ornamental design for a vase, substantially as shown.

JOSEPH GMEINDL.
